RUDOLPH GLASER, OF HALEDON, NEW JERSEY.

LET-OFF MECHANISM FOR LOOMS.

1,414,873.

Specification of Letters Patent. Patented May 2, 1922.

Application filed September 3, 1920. Serial No. 407,879.

To all whom it may concern:

Be it known that I, RUDOLPH GLASER, a citizen of the United States, and a resident of Haledon, in the county of Passaic 5 and State of New Jersey, have invented a new and Improved Let-Off Mechanism for Looms, of which the following is a full, clear, and exact description.

This invention relates to looms and has 10 particular reference to an improvement in let-off mechanisms or tensioning devices for the warp beams thereof.

The invention contemplates broadly, the provision of an automatic let-off mechanism 15 which operates to insure a constant and even tension on the warp threads under all working conditions of the loom.

Another object of the invention resides in the provision of an automatic let-off 20 mechanism which functions with equal efficiency irrespective of the weight of the material which is being operated upon.

A further object in view is to produce a device of the character described, which 25 is constructed and operates to maintain at all times an even tension on the warp threads whether the mechanism is in the act of performing its function or at rest.

A still further object accomplished by the 30 invention lies in the provision of a device of this class which includes the features of adjustability, simplicity, efficiency, and cheapness of production, installation and up-keep.

With the above recited and other objects 35 in view, some of which will appear hereafter as the nature, purpose and operation of the device is more clearly set forth in the following detail description, and the 40 appended claims, reference is made to the accompanying drawing, in which:

The figure is a fragmentary side elevation of a portion of a loom illustrating the same equipped with the let-off mechanism.

Referring to the drawings by characters 45 of reference, 10 designates a portion of the frame work of a loom which is provided with angularly disposed brackets 11, the outer extremity of which is mounted for 50 rotation on the trunnions 12, a warp beam 13 upon which the supply of warp threads 14 are wound and from which the same are fed into the loom is provided and is of the usual construction.

The automatic let-off mechanism consti-

tuting the invention comprises a friction brake band 15 connected at one extremity to a stud 16 supported from one of the brackets 11 and at its opposite extremity to a weight arm 17 which is pivoted to the stud 60 16 at one end and provided at its opposite end with a vertical aperture 18. The intermediate portion of the brake band encircles and operates in a groove 19 provided in one or both end flanges of the warp beam 65 and functions when the weight arm 17 gravitates under its own weight, to frictionally retard the rotation of the warp beam during the feeding of the warp threads 14 into the loom. In order to provide means 70 to relieve the warp beam of the frictional retarding action of the brake band 15 when the tension on the warp threads becomes excessive, use is made of an automatic compensating apparatus which comprises the rock 75 levers 20 fulcrumed between their opposite extremities as at 21 to a cross shaft. The inner extremities of the levers 20 are connected by a transverse guide bar or roller 22 over which the warp threads are trained 80 from a guide bar or roller 23 arranged transversely of the frame of the loom. From the guide bar 22 the warp threads are trained around a second guide bar or roller 24 arranged transversely of the loom 85 frame. The opposite extremities of the rock levers 20 are connected by cross rod 25 and a second cross rod 26 is arranged transversely and connects the rock levers between the fulcrum and the outer extremities 90 thereof. A vertical rod 27 is suspended from the cross rod 26 and the free threaded extremity 28 thereof passes through the vertical aperture 18 in the free end of the weight arm 17. A stop nut 29 is vertically 95 adjustable on the threaded extremity 28 of the lift rod.

In operation of the let-off mechanism, a weight 30 of the desired size is arranged on the cross rod 25 connecting the free outer 100 extremities of the rock lever. As the warp threads 14 are fed from the warp beam, the weight 30 will function to lift the inner ends of the levers 20 simultaneously lowering the lift rod 27 and disengaging the stop nut 105 29 to permit the weight of the arm 17 to retard the revolutions of the warp beam sufficiently to obtain the proper tension on the warp threads. Should the tension on the warp threads become excessive, a pull will 110

be exerted on the inner end of the levers 20 by the portion of the warp threads trained thereover, thereby lifting the outer ends of the levers against the action of the weight 5 30, thus resulting in an upward movement of the lift rod 27 and the consequent engagement of the stop nut 29 with the weight 10 arm. When the arm 17 is lifted the retarding action of the friction brake band 15 will be relieved and operate to permit free 15 revolution of the warp beam until the tension is slightly in excess of the weight carried by the outer extremities of the rock lever. It has been observed by practical demonstration that the let-off mechanism functions to maintain an even tension on the warp threads at all times, irrespective of whether the clutch band 15 or the weight 30 is functioning or whether the parts are in 20 actual operation. By employing a heavier weight 30 and adding weights to the weight arm 17, the mechanism will function with equal efficiency on heavier material and it is therefore obvious that the mechanism may 25 be employed for any grade of work.

While there has been illustrated and described a single and preferred form of the invention, it is to be understood that the right is reserved to embodiments other than 30 those actually shown, to the full extent indicated by the general meaning of the terms in which the claims are expressed and by changes in the phraseology of the same.

Having thus described my invention, I 35 claim as new and desire to secure by Letters Patent:

1. In an automatic let-off mechanism for looms, the combination with the warp beam of the loom, of a weight arm having pivotal 40 connection at one end with the warp beam support, a frictional brake band encircling the warp beam and having connection at its opposite ends with the support and the weight arm at its pivotal point whereby the 45 weight of the arm when free to move will serve to effect contraction of the band about the beam to constitute a brake for retarding its rotation, pivoted means over which the warp threads are guided from the warp 50 beam, an adjustable connection with the free extremity of the weight arm for rendering said arm inactive when tension of the warp threads become excessive, and means carried by said pivoted means for regulating the 55 amount of tension on the warp threads required to render the weight arm inactive.

2. In an automatic let-off mechanism for looms, the combination with the warp beam thereof, of a weight arm pivoted at one extremity to the warp beam support and pro-

vided with a constricted aperture in its opposite extremity, a friction brake band encircling the warp beam and having connection at its opposite ends irrespectively with the support and the weight arm at its pivot 65 whereby the weight of said arm when free to move will serve to effect contraction of the brake band about the beam to produce a braking action for retarding the rotation thereof, a rock lever pivoted between its ends to the loom frame in superposed relation to the weight arm and having a thread guide at one extremity over which the threads leading from the warp beam are trained, a lift rod connected to the rock lever on the opposite side of the pivot from the thread guide supporting extremity, the lower end of said lift rod being threaded and freely received through the constricted aperture in the warp arm, a nut mounted 80 on said threaded extremity constituting an adjustable stop adapted to coact with the under side of the free extremity of the weight arm when excessive tension of the warp threads extending through the thread 85 guide operate to exert a downward pull on the lever, and means provided on the rock lever at the opposite extremity from which the thread guide is supported for accommodating various weights whereby to regulate 90 the amount of tension necessary to lift the weight arm.

3. In an automatic let-off mechanism for looms, the combination with the warp beam, of a weight arm pivoted at one extremity to 95 the warp beam support and provided with an aperture in its opposite extremity, a friction brake band encircling the warp beam and having connection at its opposite ends with the support and the weight arm adjacent its pivot whereby the weight of the arm when free to move will serve to effect contraction of the brake band about the beam to retard the rotation thereof, a rock lever pivoted to the loom frame and having 100 a thread guide at one extremity over which the threads leading from the beam are trained, a weight supported by the opposite extremity of the rock lever, a lift rod connected to the weight arm of the rock lever 105 adjacent its pivot, the lower end of said lift rod adapted to be freely received through the aperture in the weight arm, and an adjustable stop carried by the lower end thereof and adapted to coact with the free extremity of the weight arm when excessive tension of the warp threads actuate the rock lever whereby the weight arm is rendered 110 inactive.

RUDOLPH GLASER.
